(57) **ABSTRACT**

A fan with increased heat-removing ability and reduced noise in operation includes a hub, a baffle, a first blade layer, and a second blade layer. The first blade layer includes a plurality of first blades, and the second blade layer includes a plurality of second blades. An orthogonal projection of each of the plurality of first blades on the baffle is located between orthogonal projections of adjacent two of the plurality of second blades on the baffle. A length of the plurality of first blades is greater or less than a length of the plurality of second blades to avoid any resonance. An electronic device including the fan is also disclosed.

FIG. 2

FIG. 3

FIG. 4

FIG. 5

FIG. 6

FIG. 7

FIG. 8

**FAN WITH IMPROVED HEAT DISSIPATION
PERFORMANCE AND LOW NOISE AND
ELECTRONIC DEVICE HAVING THE SAME**

FIELD

The subject matter herein generally relates to a fan and an electronic device having the fan.

BACKGROUND

Fans are used in electronic devices to dissipate heat generated by electronic components (such as chips) of the electronic devices. However, the more powerful fans are louder in operation and such noise may become troublesome.

BRIEF DESCRIPTION OF THE DRAWINGS

Implementations of the present disclosure will now be described, by way of embodiments only, with reference to the attached figures.

FIG. 1 is a diagrammatic view of a fan according to an embodiment of the present disclosure.

FIG. 2 is similar to FIG. 1, but showing the fan from another angle.

FIG. 3 is a bottom view of the fan of FIG. 1.

FIG. 4 is a diagrammatic view of a fan according to another embodiment of the present disclosure.

FIG. 5 is a diagrammatic view of a fan according to yet another embodiment of the present disclosure.

FIG. 6 shows curves of sound pressure levels with respect to speeds of fans in Example 1 and Comparative Example 1.

FIG. 7 shows curves of static pressures with respect to air volumes of the fans in Example 1 and Comparative Example 1.

FIG. 8 is a diagrammatic view of an electronic device according to an embodiment of the present disclosure.

DETAILED DESCRIPTION

Unless otherwise defined, all technical and scientific terms used herein have the same meaning as commonly understood by persons skill in the art. The terms used herein are only for the purpose of describing specific embodiments, and not intended to limit the embodiments of the present application.

In this application, descriptions such as "first", "second" etc. are only used for description purposes and should not be understood as indicating or implying their relative importance or implying the number of indicated technical features. Thus, a feature defined as "first" and "second" may expressly or implicitly include at least one of that features. In the description of the present application, "plurality" means more than one unless expressly and specifically defined otherwise.

It should be noted that when a component is referred to as being "fixed on" or "mounted on" another component, it may be directly on the other component or there may also be an intervening component. When a component is considered to be "set on" another component, it may be in direct contact with the other component or there may also be an intervening component.

Some embodiments of the present application will be described in detail below with reference to the drawings.

The following embodiments and features of the embodiments may be combined with each other in the absence of conflict.

Referring to FIGS. 1 and 2, a fan 100 is provided according to an embodiment of the present disclosure. The fan 100 includes a hub 10, a baffle 20, a first blade layer 30, and a second blade layer 50. The baffle 20 may be an annular plate, and is fixed to a middle of an outer circumference of the hub 10. The hub 10 is divided into a first part 11 and a second part 12 located on both sides of the baffle 20. The baffle 20 has a first surface 21 and a second surface 22 opposite to the first surface 21. The first blade layer 30 is arranged on the first surface 21 of the baffle 20, and the second blade layer 50 is arranged on the second surface 22 of the baffle 20.

Referring to FIGS. 1 to 3, the first blade layer 30 includes a plurality of first blades 31. The first blades 31 are arranged on the first surface 21 at equal intervals, and one end of each first blade 31 is fixed on the first part 11 of the hub 10. The second blade layer 50 includes a plurality of second blades 51. The second blades 51 are arranged on the second surface 22 at equal intervals, and one end of each second blade 51 is fixed to the second part 12 of the hub 10. Thus, the field of flowing air is uniform around the fan 100, so that the fan 100 can uniformly dissipate heat from a device to be cooled.

In other embodiments, the distances between two adjacent first blades 31 may be different from each other, which can make the natural frequency of the first blade layer 30 different from the natural frequency of the second blade layer 50, thereby reducing the noise generated by the fan 100. The distances between two adjacent second blades 51 may also be different from each other. In some embodiments, the distances between two adjacent first blades 31 or the distances between two adjacent second blades 51 may be adjusted to adjust the airflow field around the fan 100, the natural frequency of the first blade layer 30 or the second blade layer 50, and thus the noise of the fan 100.

Referring to FIGS. 1 to 3, the orthogonal projection of each first blade 31 on the baffle 20 is located between the orthogonal projections of two adjacent second blades 51 on the baffle 20. That is, the first blades 31 and the second blades 51 are staggered from each other. Thus, when the first blade layer 30 and the second blade layer 50 rotate coaxially, the airflow fields of the first blade layer 30 and the second blade layer 50 do not interfere with each other. That is, the turbulence of the airflow field at the connection of the outer periphery of the first blade layer 30 and the second blade layer 50 is avoided, eddy currents are minimal, and the heat dissipation performance of the fan 100 is improved.

Referring to FIGS. 2 and 3, the length of the first blade 31 is different from that of the second blade 51. In this way, when the first blade layer 30 and the second blade layer 50 rotate coaxially, the first blade layer 30 and the second blade layer 50 have different natural frequencies, so as to reduce resonance between the first blade layer 30 and the second blade layer 50, and further reduce the overall noise generated by the fan 100. In some embodiments, the length of the first blade 31 may be greater than the length of the second blade 51. In other embodiments, the length of the first blade 31 may be less than the length of the second blade 51.

Referring to FIGS. 1 and 2, in some embodiments, the number of the first blades 31 is the same as the number of the second blades 51, this number may be adjusted according to requirements. In this embodiment, the number of the first blades 31 and the number of the second blades 51 are the same. When the fan 100 rotates, the first blade layer 30 and the second blade layer 50 have a same volume of air

supply. In other embodiments, the number of the first blades **31** is different from the number of the second blades **51**, so that the first blade layer **30** and the second blade layer **50** have different natural frequencies, thereby reducing resonance between the first blade layer **30** and the second blade layer **50**, and also reducing the noise generated by the fan **100**.

Referring to FIGS. 1 and 5, in some embodiments, the fan **100** further includes a mute ring **40**. As shown in FIG. 1, the mute ring **40** is located at an end of the plurality of first blades **31** away from the hub **10**, and is located at a side of the first blades **31** away from the baffle **20** (i.e., located at an upper end of the first blade **31** away from the hub **10** in FIG. 1). The first blades **31** are connected to the mute ring **40**, thus the rotation of the first blades **31** is more stable, reducing vibration and thus noise. At the same time, the mute ring **40** also works to reduce deformation caused by the rotation of the first blade **31**, so as to ensure the stability of the air supply.

Referring to FIG. 4, in other embodiments, the mute ring **40** may be disposed between the first part **11** and the other end of the first blade **31** away from the first part **11**. Referring to FIG. 5, in other embodiments, the mute ring **40** may be disposed on the second blades **51**. The position of the mute ring **40** is not limited herein.

Referring to FIGS. 1 and 2, in some embodiments, the hub **10**, the baffle **20**, the first blade layer **30**, and the second blade layer **50** are integrally formed by injection molding. In some embodiments, the fan **100** may also include more than two blade layers. For the blade layers of more than two layers, a modular approach may be taken, that is, each blade layer is prepared by injection molding and then combined to form the fan **100**. The production method of the fan **100** can be adjusted according to specific production requirements.

Referring to FIGS. 1 and 2, in some embodiments, an end of the first blade **31** away from the hub **10** extends out of the baffle **20** to form a first extension portion **32**. An end of the second blade **51** away from the hub **10** extends out of the baffle **20** to form a second extension portion **52**. The orthographic projection of each second extension portion **52** on the first blade layer **30** is located between adjacent first extension portions **32**. The arrangement of the first extension portion **32** and the second extension portion **52** is convenient for processing and preparation. Along a direction from the first blade layer **30** to the second blade layer **50**, the first extension portion **32** extends toward the baffle **20** to form a protruding portion **321**. The protruding portion **321** is fixed on a side wall of the baffle **20**. The protruding portion **321** increases the stability of the connection between the first blade **31** and the baffle **20**.

Referring to FIGS. 1 and 2, in some embodiments, along the direction from the first blade layer **30** to the second blade layer **50**, the protruding portion **321** has a connecting surface **3211**. The connecting surface **3211** is a bottom surface of the protruding portion **321** facing the second blade layer **50**. The connecting surface **3211** is coplanar with the second surface **22**, which will not affect the air outlet from the second extension portion **52** and the baffle **20**, and can also ensure the stability of the connection to the baffle **20**.

Referring to FIGS. 2 and 3, in some embodiments, the fan **100** further includes a rotating shaft **60**. The rotating shaft **60** is fixed in the hub **10** along the direction from the first blade layer **30** to the second blade layer **50**. The hub **10** is also provided with a motor (not shown), the motor drives the

rotating shaft **60** to rotate, so as to drive the hub **10** to rotate, thereby realizing the rotation of the fan **100**.

Example 1

The fan in Example 1 is the above-mentioned fan **100**. A length from an end of the first blade **31** connected to the first part **11** to the first extension portion **32** is about 119 mm, and a length from an end of the second blade **51** connected to the second part **12** to the second extension portion **52** is about 113 mm. The difference between the two lengths is about 6 mm.

Comparative Example 1

The fan in Comparative Example 1 is a fan of related art (not shown). In the fan of Comparative Example 1, the orthographic projection of a first blade on a baffle overlaps with that of a second blade. That is, the distance between adjacent first blades is equal to the distance between adjacent second blades, and the length of the first blade is the same as that of the second blade. The other structures are the same as those of Example 1.

Under the same conditions, the speed-sound pressure level curve and the air volume-static pressure curve of the fan in Comparative Example 1 and the fan **100** in Example 1 are each tested.

Referring to FIG. 6, at one fixed speed, the higher the sound pressure level, the greater is the noise. At a same speed, the sound pressure level of the fan **100** provided in Example 1 is always lower than the sound pressure level of the fan in Comparative Example 1, showing that the dislocation of the first blade **31** and the second blade **51**, and the different lengths of the first blade **31** and the second blade **51**, reduce the noise generated by the fan **100**.

Referring to FIG. 7, under a same air volume, the higher the static pressure, the better the cooling effect of the fan **100**. For the same air volume, the static pressure of the fan **100** provided in Example 1 is always greater than that of the fan in Comparative Example 1, which reveals that the fan **100** in Example 1 will more quickly and efficiently draw heat away from a surface.

In the present application, the first blades **31** and the second blades **51** are staggered from each other, and the lengths of the first blades **31** and the second blades **51** are different, improving the heat dissipation performance and reducing the probability of resonance between the first blade layer **30** and the second blade layer **50**.

Referring to FIG. 8, the present application also provides an electronic device **200** including the above-mentioned fan **100**. The fan **100** is configured for dissipating heat generated within the electronic device **200**.

The above descriptions are some specific embodiments of the present application, but the actual application process cannot be limited only to these embodiments. For those of ordinary skill in the art, other modifications and changes made according to the technical concept of the present application should all belong to the protection scope of the present application.

What is claimed is:

1. A fan comprising:
a hub;
a baffle fixed to an outer circumference of the hub, the baffle comprising a first surface radially outward extending from the hub and a second surface radially outward extending from the hub and opposite to the

first surface, and the hub comprising a first part located above the first surface and a second part located above the second surface;
 a first blade layer comprising a plurality of first blades, the plurality of first blades arranged on the first surface at intervals, and an end of each of the plurality of first blades connected to the first part, another end of each of the plurality of first blades facing away from the hub radially outward extending out of the baffle to form a first extension portion; and

5 a second blade layer comprising a plurality of second blades, the plurality of second blades arranged on the second surface at intervals, and an end of each of the plurality of second blades connected to the second part; an orthogonal projection of a portion of each of the plurality of first blades on the baffle located between orthogonal projections of adjacent two of the plurality of second blades on the baffle; a length of the plurality of first blades being greater or less than a length of the plurality of second blades, wherein along a direction from the first blade layer to the second blade layer, the first extension portion extends toward the baffle to form a protruding portion, and the protruding portion is fixed on the baffle and has a connecting surface facing away from the first surface, and the connecting surface is 10 coplanar with the second surface.

2. The fan of claim 1, further comprising a mute ring, wherein the mute ring is arranged at the another end of each of the plurality of first blades away from the hub, and the mute ring is arranged at a side of the plurality of first blades away from the baffle.

3. The fan of claim 1, further comprising a mute ring, wherein the mute ring is arranged between the first part and the another end of each of the plurality of first blades away from the first part.

4. The fan of claim 1, further comprising a mute ring, wherein the mute ring is arranged on the plurality of second blades.

5. The fan of claim 1, wherein a distance between each adjacent two of the plurality of first blades is the same.

6. The fan of claim 1, wherein a distance between each adjacent two of the plurality of first blades is different from each other.

7. The fan of claim 1, wherein a number of the plurality of first blades is the same as that of the plurality of second blades.

8. The fan of claim 1, wherein a number of the plurality of first blades is different from that of the plurality of second blades.

9. The fan of claim 1, wherein the hub, the baffle, the first blade layer, and the second blade layer are integrally formed.

10. The fan of claim 1, wherein another end of each of the plurality of second blades away from the hub extends out of the baffle to form a second extension portion, and the second extension portion of each of the plurality of second blades is located between the first extension portions of adjacent two of the plurality of first blades on the baffle when viewed along an axis of the fan.

11. An electronic device comprising a fan, the fan comprising:

a hub;
 a baffle fixed to an outer circumference of the hub, the baffle comprising a first surface radially outward extending from the hub and a second surface radially outward extending from the hub and opposite to the first surface, and the hub comprising a first part located above the first surface and a second part located above the second surface;

a first blade layer comprising a plurality of first blades, the plurality of first blades arranged on the first surface at intervals, and an end of each of the plurality of first blades connected to the first part, another end of each of the plurality of first blades facing away from the hub radially outward extending out of the baffle to form a first extension portion; and

15 a second blade layer comprising a plurality of second blades, the plurality of second blades arranged on the second surface at intervals, and an end of each of the plurality of second blades connected to the second part; an orthogonal projection of each of the plurality of first blades on the baffle located between orthogonal projections of adjacent two of the plurality of second blades on the baffle; a length of the plurality of first blades being greater or less than a length of the plurality of second blades, wherein along a direction from the first blade layer to the second blade layer, the first extension portion extends toward the baffle to form a protruding portion, and the protruding portion is fixed on the baffle and has a connecting surface facing away from the first surface, and the connecting surface is 20 coplanar with the second surface.

35 12. The electronic device of claim 11, wherein another end of each of the plurality of second blades away from the hub extends out of the baffle to form a second extension portion, and the second extension portion of each of the plurality of second blades is located between the first extension portions of adjacent two of the plurality of first blades on the baffle when viewed along an axis of the fan.

40 13. The electronic device of claim 11, wherein the fan further comprises a mute ring, the mute ring is arranged at the another end of each of the plurality of first blades away from the hub, and the mute ring is arranged at a side of the plurality of first blades away from the baffle.

14. The electronic device of claim 11, wherein the fan further comprises a mute ring, the mute ring is arranged between the first part and the another end of each of the plurality of first blades away from the first part.

15. The electronic device of claim 11, wherein the fan further comprises a mute ring, the mute ring is arranged on the plurality of second blades.

16. The electronic device of claim 11, wherein a distance between each adjacent two of the plurality of first blades is the same.
